VALVE-GEAR FOR PNEUMATIC ROCK-DRILLS.

No. 837,990.

Specification of Letters Patent.

Patented Dec. 11, 1906.

Application filed June 17, 1905. Serial No. 265,649.

To all whom it may concern:

Be it known that I, CARL WEIDMANN, engineer and assistant in the Royal Polytechnic at Aix-la-Chapelle, a subject of the 5 King of Prussia, German Emperor, residing at Würselen, near Aix-la-Chapelle, in the Kingdom of Prussia, Empire of Germany, have invented certain new and useful Improvements in Valve-Gear for Pneumatic 10 Rock-Drills; and I do hereby declare the following to be a full, clear, and exact description of the invention, such as will enable others skilled in the art to which it appertains to make and use the same.

15 It is a well-known fact that pneumatic rock-drills which in the absence of an especial distributing-valve are governed by the drill-operating piston itself labor under the great disadvantage that their stroke is a very 20 limited one. Other rock-drills which are solely governed by an automatically-moved, distributing-valve show this disadvantage, that the valve-gear is not trustworthy, as the smallest retardation of the valve caused by 25 dirt and the like may cause the drill-operating piston to strike the head of its cylinder.

My present invention represents a combination of these two different ways of governing 30 a rock-drill; and its object is to do away with the disadvantages enumerated above. To this end the operation of the rock-drill is governed at the rear end of the cylinder, first, by the drill-operating piston itself and then 35 by the aid of an auxiliary distributing-valve, which controls the admission during the advance stroke and the exhaust during the back stroke to obtain a stroke of any desired length. At the front end of the cylinder the 40 drill-operating piston is solely governed by means of the auxiliary distributing-valve.

The new valve-gear may as profitably be applied to all other kinds of pneumatic tools with a reciprocating motion as it is to rock-drills.

In the accompanying drawings, Figures 1, 2, 3, and 4 are vertical longitudinal sections of a rock-drill cylinder and show the drill-operating piston and the auxiliary distributing-valve in different relations to each other. Fig. 5 is a cross-sectional view on the line 5-5 of Fig. 1. Fig. 6 is a similar view on the line 6-6 of Fig. 1.

In the cylinder 1 the drill-operating piston

2 is arranged and provided with a piston-rod 55 3, as usual. This rod is guided in the neck 4 of the cylinder 1 and carries at its free end a drill. (Not shown.) The rear end of the cylinder 1 is closed by a cylinder-head 5. In the valve-casing 6, here supposed to form an 60 integral part of the cylinder 1, the stepped auxiliary distributing-valve 7 is arranged, and the openings arranged opposite the ends of said valve are closed by the screw-plugs 8 and 9. The distributing-valve 7 is provided 65 with the annular recesses 10 and 11.

The compressed air is admitted into the casing 6 through the inlet-pipe 12, passes through the passage 13, and comes into contact with the surface 14 of the smaller end of 70 the auxiliary distributing-valve 7. In this manner this end of said valve is always kept under pressure. By means of the port 15 the surface 16 of the larger end of said auxiliary distributing-valve 7 is always kept in 75 communication with cylinder-space 17 at the rear end of the piston 2. The inlet-port 18 is at all times connected with the inlet-pipe 12 by means of the annular recess 10, whereas the exhaust is made possible through the exhaust-port 19 and the exhaust-opening 20. Between the inlet-port 18 and the exhaust-port 19 the port 21 is arranged to serve alternately as an auxiliary inlet-port or as the main exhaust-port for the cylinder-space 17, 85 which exhaust-port communicates at one time with the inlet-port 18 and at another time with the exhaust-port 19 by means of the annular recesses 10 and 11 of the valve 7. By the aid of the circumferential holes 22 90 and the longitudinal central bore or recess 23 the ports 18, 19, and 21 can be alternately brought into communication with the cylinder-space 17. Through the instrumentality of the valve 7 the port 25, communicating 95 with the cylinder-space 24 in front of the piston 2, is alternately brought into communication with the exhaust-port 19 and with the passage 13.

The operation of the new valve-gear may 100 now be explained with regard to the Figs. 1, 2, 3, and 4.

In Fig. 1 the drill-operating piston 2 is moving backward under the influence of the pressure which exists in the cylinder-space 105 24. The circumferential holes 22 of the piston have just commenced to uncover the inlet-port 18, so that the cylinder-space 17 at

the rear of the piston 2 is supplied with compressed air and the direction of travel of the piston 2 reversed. At the same time pressure is exerted upon the larger surface 16 of the valve 7 by way of the port 15, and thus the valve 7 compelled to take up the position shown in Fig. 2, since the surface 16 is larger than the surface 14. Fig. 2 shows that in this position of the auxiliary distributing-valve 7 the annular recess 10 connects the port 21 with the inlet-port 18 in such a manner that when the circumferential holes 22 are situated in front of the port 21 during the advance stroke of the piston 2 a second admission, the so-called "auxiliary" admission, of compressed air into the cylinder-space 17 takes place. At the same time the valve 7 brings the port 25 and the cylinder-space 24, connected therewith, in communication with the exhaust-port 19 and with the exhaust-opening 20 by means of the annular recess 11, and thus permits the piston 2 to further advance under the pressure existing in the cylinder-space 17.

In Fig. 3 is shown how during the advance of the piston 2 the circumferential holes 22 commence to uncover the exhaust-port 19, through which the compressed air which fills the cylinder-space 17 now may enter the exhaust-opening 20 and escape. Simultaneously herewith the compressed air, acting upon the surface 16 of the valve 7, escapes through the port 15, so that the pressure acting upon the smaller surface 14 of the valve 7 can move the latter into the position shown in Fig. 4, during which operation the piston 2 accomplishes the blow.

Fig. 4 shows how during the time the valve 7 remains in the position indicated therein the port 25 and the cylinder-space 24 keep up communication with the passage 13 and with the inlet-pipe 12 and how the piston 2 is driven back again by the pressure existing in the cylinder-space 24. Fig. 4 further shows how the annular recess 11 connects the port 21 with the exhaust-port 19 and with the exhaust-opening 20, so that when the circumferential holes 22 of the piston 2 commence to uncover the port 21 during the back stroke of the piston 2 another exhaust, the so-called "auxiliary" exhaust, from the cylinder-space 17, takes place. When during the further advanced back stroke of the piston 2 the circumferential holes 22 again begin to uncover the admission-port 18, the cycle of operations described above begins anew.

To vouchsafe a correct working of the valve-gear without any loss of compressed air, the distance between the ports 18 and 21, on the one hand, and between the latter and the port 19, on the other hand, must be greater than the length of the holes 22 in the circumference of the piston 2, so that these holes cannot communicate with two of these ports at the same time.

Though considering the present arrangement of parts as the most advantageous, minor changes in the details of construction and arrangement of parts may be resorted to without departing from the spirit of my invention. 70

I claim—

1. In a valve - gear for pneumatic rock-drills, the combination with a cylinder, of a valve-casing, a stepped auxiliary distributing - valve with annular external recesses, an inlet-port constantly communicating with one of said recesses, an exhaust-port constantly communicating with the other of said recesses, an auxiliary port communicating with the inlet-port when said valve is placed in one end position and with said exhaust-port when said valve is placed in the other end position, a drill-operating piston reciprocating in said cylinder, a longitudinal open recess in said piston, and circumferential holes in said piston communicating alternately with said inlet-port, said auxiliary port, and said exhaust - port and always through said recess in communication with the cylinder-space communicating with the larger end surface of said valve to permit by means of the latter and said auxiliary port the admission of air to the rear end of said piston during the advance stroke after the inlet-port has been covered by said piston and by the same means keep the exhaust from the rear end of said cylinder open during the back stroke after the exhaust-port has been covered by said piston. 100

2. A valve-gear for pneumatic rock-drills comprising a cylinder, a valve - casing, a stepped auxiliary distributing - valve with annular external recesses, an air-inlet always communicating with the smaller end surface of said valve, a port communicating with the larger end surface of said valve and with the rear end of said cylinder, an inlet-port constantly communicating with one of said recesses, an exhaust-port always in communication with the other of said recesses, an auxiliary port situated between said inlet-port and said exhaust-port and communicating with the inlet-port when said valve is placed in one end position and with the exhaust-port when said valve is placed in the other end position, a drill - operating piston, a longitudinal open recess therein, circumferential holes in said piston communicating alternately with said inlet - port, said auxiliary port and said exhaust - port and always through said recess in communication with the rear end of said cylinder to maintain the admission of air to the rear end of said cylinder during the advance stroke by means of said valve and said auxiliary port after the inlet-port has been covered by said piston and by the same means keep the exhaust from the rear end of said cylinder open during the back stroke after the exhaust- 115 120 125 130

port has been covered by said piston, an exhaust-opening communicating with the valve-bore, and a port connecting the front end of said cylinder with said valve-bore and communicating with said air-inlet when said valve is placed in one end position and communicating with the exhaust-opening when said valve is placed in the other end position.

In testimony whereof I have signed my name to this specification in the presence of 10 two subscribing witnesses.

CARL WEIDMANN.
